US00D613599S

(12) **United States Design Patent**
Khubani

(10) **Patent No.:** **US D613,599 S**
(45) **Date of Patent:** **** Apr. 13, 2010**

(54) **BEVERAGE CONTAINER CLOSURE WITH
PRESSURE RELEASE**

(75) Inventor: **Ajit Khubani**, Saddle River, NJ (US)

(73) Assignee: **Telebrands Corp.**, Fairfield, NJ (US)

(**) Term: **14 Years**

(21) Appl. No.: **29/316,302**

(22) Filed: **Sep. 11, 2009**

(51) **LOC (9) Cl. 09-07**

(52) **U.S. Cl. D9/446; D9/449**

(58) **Field of Classification Search D9/454,
D9/449, 447, 443, 438, 435, 428, 446; D7/608,
D7/510, 396.2, 392.1, 392; 229/906.1; 220/713,
220/712, 711, 270, 254.1-254.9, 258.2, 375;
215/306; D3/264**

See application file for complete search history.

(57) **CLAIM**

The ornamental design for a beverage container closure with pressure release, as shown and described.

DESCRIPTION

FIG. 1 is a perspective view thereof;

FIG. 2 is a side view thereof, the other side view thereof being a mirror image of this side view;

FIG. 3 is a top view thereof;

FIG. 4 is a front view thereof;

FIG. 5 is a bottom view thereof; and,

FIG. 6 is a back view thereof.

The broken lines in FIGS. 1-6 depict environment only and form no part of the claimed design.
